FREDERICK J. ROOT, OF RIDGEWOOD, NEW JERSEY, ASSIGNOR, BY MESNE ASSIGNMENTS, TO SIPP EASTWOOD CORPORATION, OF PATERSON, NEW JERSEY, A CORPORATION OF NEW JERSEY

WINDING MACHINE

Application filed September 11, 1928. Serial No. 305,153.

This invention relates to winding machines and in particular to the traversing thread-guide rail by which the yarn or thread is guided to the spools or bobbins and made to traverse back and forth along the same as the winding proceeds. The rail structure usually includes the rail proper and a series of guides, usually porcelain, which are held in place by wire spring members alternating with them, each two guides being held by an intermediate spring member by having its extremities overlapping them and seated in grooves in the two guides. This construction permits each guide to be slipped along one way or the other, as by tapping it, to adjust it in proper or centered relation to the corresponding spool (it being recognized that if it is not so centered the windings will pile up against one head and form a channel next to the other head of the spool), but it is faulty in that the adjustment cannot be effected to a nicety without great care and that in any event the reciprocating movement of the rail structure soon disturbs it, so that constant attention is required by some skilled person to keep all the guides accurately positioned. Among other objects of this invention the principal one is to provide a thread-guide rail structure in which the guides are adjustable longitudinally and when once set or adjusted will remain so without further attention. In the example herein set forth I retain the guides and springs substantially as they have heretofore usually been formed, but the thread-guiding device includes with the guide a plate or slide and the rail member includes the rail proper and a base for the guiding device attached to the rail proper.

In the drawings,

Fig. 1 is a front elevation of sufficient of a winding machine to illustrate the invention; Fig. 2 is a fragmentary front elevation of the improved rail structure, with the rail proper partly in section; Fig. 3 a section thereof on line 3—3, Fig. 2, with the spring omitted and the rail guide bracket included;

Fig. 4 is a plan of the guide, the slide and base; and

Figs. 5 and 6 are plans of parts 7 and 9, respectively.

The horizontally extending rail proper 1 is by any means reciprocated in the brackets 2 of the winding machine opposite the suitably supported horizontally alined spools or bobbins 3, and it has secured thereto on its top surface by screws 4 the elongated bent springs 5, each being so secured at its midportion and having its ends reaching in opposite directions lengthwise of and inclined toward the rail. So much is the usual construction. Each thread guide 6 has the usual form, being a block (as of porcelain) with a top cross-cut notch 6a for the yarn and two longitudinal top notches 6b which receive said ends of the spring; its end surfaces converge upwardly.

A base member 7, consisting of an elongated plate having an upturned end 7a, is seated on the rail proper and may have a pair of depending longitudinally alined and spaced tangs 7b which enter the groove 1a in the top of the (wooden) rail 1, being a little wider than such groove so that under pressure they bite or are pressed into its sides sufficiently to obtain a hold against longitudinal displacement; the rail proper and the base member may have marks or notches 8 to gage the proper position of the latter opposite the spool.

On the base member is arranged the slide 85 9, consisting of an elongated plate having the end 9a thereof corresponding to end 7a of member 7 upturned. It also has two upstanding clips 9b, upwardly converged, and these receive the guide in the manner shown, the plate of member 9 being somewhat elastic so that the clips act to clamp the guide, which may have a dowel 6c to enter a slot or recess 9c in the plate, which in turn may have dowels 9d to enter a slot or recess 7c in the base.

The upturned ends 7a and 9a form lugs receiving a thumb-screw 10 which is swivelled in one of them (as 9a) and tapped into the other.

Thus, while my thread-guide rail structure remains substantially as before so far as the guiding of the thread or yarn is concerned—in particular the ends of the springs serving to insure return of the thread or yarn to the guiding notch should it leave the same—adjustment, practically of micrometer character, is possible, and when once effected remains permanent, mainly because a screw is used and also because vibration or movement of the thread-guide device (here including parts 6—9) on the rail member (here including parts 1—7) is, independently of the screw, resisted by the spring, which is retained largely for this reason. The spring, further, exerting pressure through said device and the base holds the former against the latter and the latter against the rail proper, the base being preferably held against any lateral movement on the rail proper by the described engagement of its tangs therewith and said device against such movement by the screw and its dowel connection with the base.

In these structures the thread frequently leaves the notch 6a of the guide and considerable winding thereupon proceeds without traverse, which of course produces a faulty package. The end portion of the spring 5 being inclined downwardly toward the guide from a point remote therefrom insures the automatic return of the thread to the groove in every instance where it is unshipped from the groove, so that faulty winding from the cause indicated is not possible.

Having thus fully described my invention, what I claim is:

1. A thread-guide device comprising a plate and a thread-guide, the plate having opposed clamping means integral therewith and projecting from one face thereof and exerting pressure on opposite upright faces of the thread guide, and said plate and thread-guide having an interengaged dowel and recess holding the thread guide against slippage transversely of the line of clamping pressure and in a plane parallel with that of the plate.

2. A thread-guide structure for a winding machine including a rail member, a thread-guide, and a plate interposed between the thread-guide and said member and having on the face thereof adjoining the thread-guide a pair of upstanding portions integral with the plate and offset from each other lengthwise of said structure and between which the thread guide is arranged and held, said member and plate having an interengaged dowel and recess.

3. A thread-guide rail structure for a winding machine including a rail-proper, a base seated on the rail-proper and adjustable along the same, a thread-guide device carried by the base, said rail-proper and base having a tongue-and-groove connection extending lengthwise of the rail-proper and

serving to guide the base when adjusted along the rail, and said rail-proper and base being formed one to clinch the other when the base is pressed toward the rail-proper, and spring means on the rail-proper pressing the base toward the same.

In testimony whereof I affix my signature.

FREDERICK J. ROOT.
